CLAIM

The ornamental design for a medical sample diagnostic analyzer, as shown and described.

DESCRIPTION

FIG. 1 is a perspective view of the medical sample diagnostic analyzer.

FIG. 2 is a front view of the medical sample diagnostic analyzer.

FIG. 3 is a back view of the medical sample diagnostic analyzer.

FIG. 4 is a first side view of the medical sample diagnostic analyzer.

FIG. 5 is a second side view of the medical sample diagnostic analyzer.

FIG. 6 is a top view of the medical sample diagnostic analyzer; and,

FIG. 7 is a bottom view of the medical sample diagnostic analyzer.

The broken lines are included for the purpose of illustrating portions of the medical sample diagnostic analyzer that form no part of the claimed design.

1 Claim, 7 Drawing Sheets
